(57) **CLAIM**

The ornamental design for a female shelf connector for corrugated material, substantially as shown and described.

DESCRIPTION

FIG. 1 is a front perspective view of a female shelf connector for corrugated material showing my new design;

FIG. 2 is a front elevational view thereof;

FIG. 3 is a right side elevational view thereof, the left side (not shown) being a mirror image thereof;

FIG. 4 is a rear elevational view thereof;

FIG. 5 is a top plan view thereof; and,

FIG. 6 is a bottom plan view thereof.
